UNITED STATES PATENT OFFICE.

ORVILLE R. GALBRAITH, OF ASQUITH, SASKATCHEWAN, CANADA.

INTERNAL-COMBUSTION ENGINE.

1,301,420.

Specification of Letters Patent. Patented Apr. 22, 1919.

Application filed January 3, 1918. Serial No. 210,218.

To all whom it may concern:

Be it known that I, ORVILLE R. GALBRAITH, a subject of the King of Great Britain, residing at Asquith, in the Province of Saskatchewan, Canada, have invented a new and useful Internal-Combustion Engine, of which the following is a specification.

The present invention relates to internal combustion engines, and more particularly to those of the two-cycle type.

The invention has for an object to provide a relatively compact and simply constructed engine of the two-cycle type, and wherein the piston receives impact at opposite ends 15 of its stroke to force the piston first in one direction and then in the other to increase the power of the engine over engines of a similar type and size.

The invention further aims at the provision of a piston which controls the inlet and exhaust ports and compresses and forms chambers for the charge as well as effecting the expulsion of burnt gases.

The invention also provides an engine 25 wherein the cylinder and piston thereof are peculiarly associated to form between them a charged receiving chamber which opens first at one side of the piston, and subsequently opens at the other side of the piston; and to provide the engine with a peculiar head or closure forming a guide for the piston and means for cooling the same.

The above, and various other objects and advantages of this invention will in part 35 be described, and in part be understood from the following detailed description of the present preferred embodiment, the same being illustrated in the accompanying drawings, wherein:

40 Figure 1 is a side elevation of an internal combustion engine constructed according to the present invention.

Fig. 2 is a vertical longitudinal section taken through the engine showing the piston at the inner end of its stroke.

Fig. 3 is a similar view, showing the piston at the outer end of its stroke.

Referring to these drawings, 10 designates the body portion or cylinder of the engine 50 which is elongated and provided at its forward end with an annular partition wall 11 providing between the wall 11 and the for-

ward end of the cylinder 10 a water jacket or cooling space adapted to receive a cooling medium therein. The partition 11 also 55 forms a contracted bore at the forward end of the cylinder within which is slidably mounted a piston 12. The piston 12 is connected at its outer or forward end to a connecting rod 13 which is longitudinally movable through a stuffing box 14 fitted through the outer end of the cylinder 10. The piston 12 is provided on its forward end, and near its upper side with a deflector 15 formed preferably integral with the piston and constituting a transversely extending projection or lip. Packing rings 16 are fitted about the forward end of the piston 12 and engage the inner wall of the cylinder. A spark plug 17 is fitted through the outer end of the 70 cylinder.

The inner end of the piston 12 is formed with an annular outstanding flange 18 adapted to fit at its periphery against the inner wall of the cylinder at the enlarged inner 75 end thereof, and is provided with a packing ring 19 adapted to seal the flange 18 in the cylinder. The inner end of the cylinder has an annular partition wall 20 which forms a charge receiving passage 21 between the 80 cylinder 10 and the wall 20. The passage 21 extends substantially half way around the upper part of the cylinder and communicates at said portion of the cylinder with the charge compression chamber 22 formed concentrically within the wall 21.

The cylinder 10 has an inlet port 23 at the forward end of the passage 21 and located in the upper side of the cylinder and adapted to be opened and closed by the piston 12. 90 The chamber 22 and the passage 21 intercommunicate only at the inner end of the cylinder, and flange 18 is adapted to move with the piston longitudinally in the annular charge compressing chamber 22.

The cylinder 10 is provided with a removable head 24 adapted to fit into the inner end of the cylinder in spaced relation to the annular wall 20 and projects into the inner open end of the piston 12. The piston 12 is 100 hollow and when moved inwardly is adapted to receive the head 24 therein, as shown in Fig. 2. The head carries packing rings 25 for slidably engagement with the inner wall

of the piston 12 to seal the head therein, and is of hollow construction to form a chamber 26 for the reception of a cooling medium. The rear end of the head 24 is enlarged to 5 form a cap plate 27 adapted to fit against the inner end of the cylinder 10 to close it, and is held in place by machine screws, or the like, for retaining the head 24 in position.

- 10 The head 24 is of a length equal substantially to one half the length of the cylinder 10 and forms the inner wall of the annular compression chamber 22. The piston 12 has an inlet port 28 in its upper side and at its 15 inner end adapted to be opened by the forward movement of the piston sufficiently to carry the port 28 beyond the inner end of the head 24. The port 28 intercommunicates the compression chamber 22 with the interior 20 of the piston 12 when the latter is in its outermost position.

The lower side of the cylinder 10 is provided with a pair of longitudinally spaced apart exhaust ports 29 and 30 which communicate respectively with the interior of the piston 12 through port 31 thereof when the piston is in its foremost position, and with the interior of the cylinder 10 at its forward end when the piston is in its innermost position. An exhaust manifold 32, of cupshape, is threaded into the lower side of the cylinder 10 and communicates with both of the exhaust ports 29 and 30 to carry off the products of combustion from the engine. An exhaust pipe 33 leads from the manifold 32 to any suitable point of discharge.

The cylinder 10 also has in its lower side, and at its inner end a pair of spaced apart 40 inlet ports 34 and 35 which open into the opposite ends of the compression chamber 22. The port 34 is larger than the port 35 and opens into the rear end of the chamber 22 which also communicates with the passage 21 and the larger combustion chamber formed in the forward end of the cylinder 10. Inlet valve casings 36 are secured to the lower side of the cylinder 10 over the ports 34 and 35 and are provided with outwardly 45 seating valves 37 normally held to their seats by adjustable springs 38 located exteriorly of the casings 36. An intake manifold 39 has its branches connected to the valve casings 36 to supply the charge thereto, and 55 leads from a carburetor 40 of any adaptable type.

The head 24 has upon its inner end a deflector 41 similar in formation and location to the deflector 15 of the piston, and the 60 head is provided with a relatively long spark plug 42 which extends entirely through the head and has its electrodes arranged at the inner end of the head below the deflector 41.

The cylinder 10 is provided at opposite 65 sides with one or more bracket lugs 43 by

means of which the cylinder may be mounted in a frame or on any other suitable support. The piston rod 13 may of course be connected to any suitable power transmission mechanism for transmitting motion of 70 the piston 12 in any suitable manner.

In operation, when the piston 12 is in its forward position as shown in Fig. 3, a charge is compressed in the forward end of the cylinder 10 and the inlet port 28 of the 75 piston communicates the forward end of the compression chamber 22 with the interior of the piston. Immediately prior to the opening of port 28, the port 31 registers with the exhaust port 29 and the consumed gases 80 within the piston 12 are permitted to escape into the exhaust manifold 32, the deflector 41 directing the gases toward the port 31 and preventing, to a large extent, the admixture of the incoming charge entering 85 through port 28 with the outflowing consumed products of combustion.

During the forward stroke of the piston the flange 18 moves forwardly in the chamber 22 and creates a partial vacuum in the 90 inner end of the chamber 22 which draws a new charge into the chamber in rear of the flange 18 through the intake port 34. During this forward movement of the piston the charge contained in the chamber 22 in front 95 of the flange 18 is compressed thereby owing to the fact that the port 28 is closed by the head 24. The compressed charge is released only when the piston 12 is in its foremost position.

100 Sparking at the plug 17 explodes the charge in the forward end of the cylinder 10, and the impact drives the piston 12 to its innermost position as shown in Fig. 2. During this rearward movement of the piston, the flange 18 compresses the charge in the 105 rear end of the chamber 22 and in the passage 21, the charge being released only when the piston reaches its innermost position to uncover the port 23. The flange 18, while thus compressing the charge in the rear end of the chamber 22 creates a partial vacuum in the forward end of the chamber and draws in a new charge through the port 35. As the piston 12 nears the completion of its 110 rearward stroke it uncovers the exhaust port 30 and releases the expanding consumed gases from the forward combustion chamber, and on reaching its innermost position uncovers the port 23 and admits the new 115 charge to the forward combustion chamber. This cycle of operations is repeated during the reciprocation of the piston. Spark occurs at the inner end of the plug 42 when the piston 12 reaches its innermost position 120 to explode the charge in the inner combustion chamber.

125 It is of course understood that various changes and modifications may be made in the details of construction and design of the 130

above specifically described embodiment of this invention without departing from the spirit thereof, such changes and modifications being restricted only by the scope of 5 the following claims.

What is claimed is:

1. In an internal combustion engine, the combination of a cylinder having an enlarged bore at one end and a counter bore at 10 its other end, a piston fitting in the bore and having an inner chamber open at one end and provided thereat with an outstanding flange adapted to engage the wall of the counter bore, and a head closing the end of the cylinder and projecting into the open end of the piston to close the same, the head and the piston forming a charge receiving chamber within which said flange is adapted to move, the cylinder having ports 15 communicating the opposite ends of said chamber with the interior of the piston and the forward end of the cylinder and adapted to be controlled by movement of the piston, said piston having ports adapted to register 20 with the ports of the cylinder to alternately open said chamber to the interior of the piston.

2. In an internal combustion engine, the combination of a cylinder having a bore and 30 a counter bore, a piston fitting in the bore and being open at one end and having an enlargement fitting in said counter bore, and a head closing the end of the cylinder and projecting into the piston to close the same, 35 the cylinder and the head forming a charge receiving chamber adapted to receive the charge by suction created by movement of the enlargement in the chamber, the cylinder having a passage leading from one end 40 of said chamber, and the piston having a port opening into the chamber and adapted to be uncovered by the head when the piston moves forwardly therein, said piston being adapted to uncover the passage in the cylinder 45 when the piston moves inwardly over the head.

3. In an internal combustion engine, the combination of a cylinder having a bore and a counter bore, a piston fitting in the bore, 50 and a head fitting in the counter bore of the cylinder and in the end of the piston, the head and the cylinder forming a charge receiving chamber, the cylinder having an inlet port at each end of the chamber and having 55 a passage leading from the chamber to the bore adapted to be open when the piston is moved inwardly, said cylinder also having an exhaust port adapted to be uncovered by the piston when moved inwardly 60 and having a second exhaust port, said piston having an enlargement movable in said chamber to alternately compress a charge in the opposite ends of the chamber and having an inlet port leading to the chamber and adapted to be uncovered by the head when

the piston is moved forwardly, said piston also having a discharge port adapted to register with said second exhaust port of the cylinder when the piston is moved forwardly.

70

4. In an internal combustion engine, the combination of a cylinder having a bore and a counter bore and provided with an inlet port at each end of the counter bore and a passage leading from the inner end of the bore to the counter bore, a hollow piston adapted to fit in the bore and having an enlargement fitting in the counter bore to alternately draw in a charge through said inlet ports and compress the charge in the 75 counter bore at opposite sides of the enlargement, said piston being adapted to uncover said passage when the piston is moved inwardly, and a head carried by the cylinder and projecting into the piston to close it, 80 said piston having an inlet port adjacent the enlargement adapted to be uncovered by the head when the piston moves forwardly.

85

5. In an internal combustion engine, the 90 combination of a cylinder having a bore and a counter bore, inlet ports at the opposite ends of said counter bore, exhaust ports intermediate its ends and a passage leading from the inner end of the counter bore to 95 the bore, a piston slidable in the bore and having an enlargement fitting in the counter bore to draw in charges through said ports and compress the charges at the opposite sides of the enlargement, said piston being 100 adapted to uncover said passage when moved inwardly to admit a compressed charge into the bore and having an inlet port adapted to admit a compressed charge to the interior of the piston when moved 105 forwardly, said piston being adapted to uncover said exhaust port when moved inwardly and having a port adapted to register with the exhaust port when the piston is moved outwardly.

110

6. In an internal combustion engine, the combination of a cylinder having a bore and a counter bore, a piston fitting in the cylinder, and a head projecting into the counter bore and fitting in the piston, said piston 115 having an enlargement fitting in the counter bore to compress charges alternately at the opposite sides of the enlargement and provided with a port adapted to be uncovered by the head to admit a compressed charge 120 to the interior of the piston, said cylinder having an inlet passage leading from the counter bore to the bore to be uncovered by the piston and admit a charge into the bore, the cylinder having an exhaust port adapted 125 to be uncovered by the piston to admit escape of the gases from the bore and having a second exhaust port, and the piston having an exhaust port adapted to register with said second exhaust port of the cylinder.

der to admit escape of gases from the interior of the piston.

7. In an internal combustion engine, the combination of a cylinder having a bore and a counter bore and having inlet ports and exhaust ports, a piston fitting in the bore of the cylinder and having an enlargement

movable in the counterbore to create suction therein, the piston being adapted to control said inlet and exhaust ports and provided with inlet and exhaust ports, and a head in the cylinder fitting in the piston to control the inlet and exhaust ports thereof. 10

ORVILLE R. GALBRAITH.
